Inventor:

Jasper S. Jenett.

United States Patent Office

JASPER S. JEWETT OF OTTAWA, ILLINOIS.

Letters Patent No. 77,492, dated May 5, 1868.

IMPROVEMENT IN FENCE-GATES.

The Schedule referred to in these Letters Patent and making part of the same.

TO ALL WHOM IT MAY CONCERN:

Be it known that I, JASPER S. JEWETT, of Ottawa, in the county of La Salle, in the State of Illinois, have invented a new and improved Fence-Gate; and I do hereby declare that the following is a full and exact description thereof, reference being had to the accompanying drawings, and to the letters of reference marked thereon.

The nature of my invention consists in a certain improvement in fence-gates, and in a novel manner of constructing the same, whereby a person on a wagon or on horseback is enabled to open and close the gate, without descending to the ground or anyways disturbing his position, as the rings which are to be pulled to operate the gate are overhead in the middle of the track.

My invention also consists in providing an arrangement of springs, catches, and levers, by means of which the gate is locked, so that no rooting hog or other animal can possibly open the gate, as often happens with gates in which there is no locking-arrangement provided.

To enable others skilled in the arts to make and use my invention, I will proceed to describe its construction and operation.

Figure 1, in the drawings, is a vertical plan of the gate when closed.

Figure 2 is a horizontal plan.

Figure 3 is a section through *a b*, fig. 2.

Figure 4 is a vertical section representing the mechanism by means of which the gate is locked and unlocked.

I set deeply into the ground two double posts, *A A*, which are connected at the top by the framework made of the timbers *B B B*. The gates *C C* reach half way each, and meet at the centre. These gates *C C* are supported at the centre by the block *D*, which is a short post sunk into the ground. At each end the gates *C C* are supported on two pivots, *E E* and *F F*, on which they swing up and down. The top rails, *G G*, of the gates *C C* are hollow, in order to admit a string or chain, as will be described hereafter. Each of these top rails *G G* projects through the posts *A A*, the outer ends being loaded with weights, in order to counterbalance the weight of the gates *C C*. To the hinges or tumblers *H H* are attached the rods *I I*, which communicate above with the levers *J J*. These levers swing on the fulcra *K K*, and their inner ends are inserted into a hollow casting, *L*. Said casting *L* is made in the shape of a hollow cross, and has two more levers, *M M*, inserted into it, which swing on the fulcra *N N*, and which have attached at their outer ends the ropes *O O*, with rings at their ends. The object of the hollow casting *L* is that all the levers, *J J* and *M M*, connected with it, must move together, their radiating disposition not allowing said hollow casting *L* to swing sideways, but only to go straight up and down.

It will be seen that by pulling either of the ropes, *O O*, the motion will be communicated through the rods *I I* to the gates *C C*, causing both to open at the same time, by folding up on each side and between the posts *A A*, as shown by the lines in red, fig. 1. Two ropes, *O' O'*, pass through the casting *L*, and over and around the pulleys *l l l l*, terminating in rings.

By pulling either of the ropes *O' O'*, when the gate is open, the casting *L*, being thereby pulled downwards, carries with it the levers *J J* and rods *I I*, thus causing the gates *C C* to swing down and close.

In fig. 4 is shown the mechanism by which the gates *C C* are locked when let down. The central uprights, *P P*, of the gates *C C* are made hollow, and contain the iron catches *Q Q* and springs *R R*. Ropes or chains, *S*, pass from the catches *Q Q* to the hinges or tumblers *H H*.

As shown by the lines in red, fig. 4, when the rods *I I* are pressed down, the tumblers *H H* are thrown backwards, pulling the strings or chains *S*, and thus causing the catches *Q Q* to escape their hold on the bolts *T T* in the block *D*. Two springs, *U U*, are adapted to throw up the tumblers *H H* in their original position after the gates *C C* are let down and locked.

What I claim as my invention, and desire to secure by Letters Patent, is—

1. The two gates *C C*, the rods *I I*, the levers *J J*, the levers *M M*, the hollow casting *L*, the ropes *O O*, and

the ropes O' O', when combined with each other in a double fence-gate, and constructed substantially as and for the purpose described in the foregoing specification.

2. The catches Q Q, the ropes or chains S, the tumblers H H, the springs R R, and the springs U U, when combined with each other in a double fence-gate, and constructed substantially as and for the purpose described in the foregoing specification.
